SHUTTLE DRIVING MECHANISM FOR
WEAVING LOOMS OR MACHINES

Willi Keil, Krefeld, Germany

Application September 29, 1952, Serial No. 311,990

10 Claims. (Cl. 139—136)

1 In weaving looms or weaving machines herein-after in this specification and the claims hereof called looms, the shuttle is caused to travel through the shed usually in flat looms by an impulse imparted to the shuttle which ejects it from its box at one side of the shed and causes it to fly freely through the shed until braked or brought to a stop in the box at the opposite side of the shed and set in motion afresh in the opposite direction. In circular looms it has been proposed instead of driving the shuttle by impulse or impact, to drive it forward positively on its circular path in a direction which is always unidirectional but the driving means is comparatively complicated and is only adapted to be used on circular looms. The customary sudden pro-jection of the shuttle in flat looms is disadvantageous on account of the heavy wear of driving parts associated therewith.

An object of the invention is to provide a loom wherein the shuttle is positively moved throughout its path through the shed usually in both directions, the drive taking place through the lower threads of the shed.

To this end, the present invention broadly consists in shuttle driving mechanism for positively moving the shuttle of a loom preferably in both directions, through its shed, comprising in combination, a shuttle, guiding means therefor, a slide, preferably a reciprocating slide, arranged externally of said shed, means for moving said slide transversely of the general direction of the warp threads, a rack parallel to the direction of and stationary with respect to the said movement of said slide, a gear wheel operatively related to said slide so as to be movable positively therewith and engaging said rack for rotation thereby during movement of said gear wheel with said slide, said gear wheel being in operative relation to said shuttle so that the said gear wheel and shuttle move together in passage of the shuttle through the shed and being adapted to mesh with the lower warp threads in rolling along said rack.

The aforesaid guiding means may be in the form of a reed-like notched bar passaged for the guidance of the shuttle, the edges of the notched bar directed towards the shed angle nearer to the cloth roller collectively serving as a beater for the weft threads, the notched bar serving for separating warp threads, beating-up weft and acting as a tubular race for the shuttle.

Notched strips may be provided for the warp threads disposed at or towards both sides of the shuttle track and particularly below the shuttle, 55

2 a plurality of warp threads being laid in the notches of said strips which notches are so spaced that gaps of sufficient width are formed in the lower sheet of warp threads for the passage of the teeth of a gear wheel as aforesaid.

The reed serving elements of the notched bar may be so arranged in circular formation that they form an endless channel.

In one constructional form of the present in-vention the drive arrangement is such that the lower threads of the shed come between gear wheels which engage from opposite sides of the lower sheet of warp threads aforesaid.

More particularly, three gear wheels one large and two small whose engagement is effected through the lower sheet of warp threads are em-ployed, said gear wheels intermeshing by means of their teeth with the lower warp threads lying between the addendum and root circles of the respective wheels. The two smaller gear wheels which are not in mesh with one another are arranged to be freely rotatable on a slide which, arranged without the shed, is movable transver-sely of the warp threads. The third wheel is ro-tatably mounted on the shuttle and engages similtaneously in a rack which is disposed below the lower sheet of warp threads of the shed. But for the rack the trailing wheel of the gear wheels of the moving slide would set the gear wheel of the shuttle in bodily movement only, transversely of the warp threads but in the presence of the rack the said shuttle gear wheel is caused to roll on the rack.

The advantage of this arrangement consists in that the shuttle can be moved with a uniform movement positively from one side of the shed to the other and consequently minimize wear, such as is caused in customary looms by the im-pact drive. Owing to the positive drive for the loom shuttles, the conditions at the points of reversal of the movement can be more easily con-trolled mechanically, and it is consequently also possible to operate with a larger number of wefts than hitherto.

45 For the purpose of guiding the shuttle, there is provided a channel or race, preferably a tubular race, such as was hitherto only occasionally used in connection with circular looms, said race comprising apertured spaced plates carried by a slot-ted bar and adapted to receive the warp threads therebetween in the manner of a reed. The guid-ing cross-section of the race may be of a shape, e. g., round or angular, adapted to the shape of the shuttle. The race also serves the purpose of a reed in beating up the pick of weft to the "fell"

or edge of the material. For this purpose, the tubular race aforesaid is mounted to make the beating up movement of the sley of a loom, the guide track of the aforesaid driving slide participating in this movement.

While the shuttle carries the pick of weft through the shed, the lower threads of the shed successively lie between the teeth of the three interengaging gear wheels. In certain circumstances, the fact that the threads are disposed between the teeth of the gear wheels which are in engagement with one another can lead to damage to the threads. For avoiding this inconvenience, therefore, it is advantageous to bunch or group the threads, so that they are 15 jointly disposed in gaps which are formed between the interengaging teeth. For this purpose, notched or saw-toothed guide strips may be arranged at both sides of the shuttle path, particularly beneath the shuttle. A plurality of warp 20 threads are disposed in the lower vertices of these saw-toothed guide strips and are in this way bunched or grouped. On account of this bunching, or grouping of the lower threads, gaps are formed between the lower sheet of warp threads 25 through which the teeth of the gear wheels are able freely to pass, while the bunched threads are received in the gaps which are formed between the tooth crests of one of the wheels and the tooth roots of the other wheel.

In another constructional form of the invention, there is arranged on the reciprocating slide a gear wheel which engages through the aforesaid bunched warp threads in a recess of the shuttle which is rounded to correspond to the addendum circle of the gear wheel. Said gear wheel also engages in a rack disposed below the lower threads of the shed. When the slide carrying this gear is moved backwards and forwards transversely of the warp threads, the gear wheel is set in rotation by rolling along the rack, whereby the tips of the teeth of said gear wheel exert a pushing force in the required direction of movement on what for the time being is the leading end of the rounded recess of the shuttle. The shuttle is consequently driven along by the gear wheel as it moves backwards and forwards with the slide.

In order to facilitate the rotational movement of the gear wheel, for the purpose of meshing with the warp threads of the shed below the shuttle, the tips of the teeth of said gear wheel may be provided with anti-friction means, e. g., rollers or the like.

Driving mechanism according to the last mentioned constructional form of the invention has the advantage of working with few rotating and intermeshing parts, so that less supervision and lubrication is required.

Two preferred constructional forms of the invention are shown in the drawings, with reference to which the invention will now be more fully explained; and in which:

Figs. 1 to 6 illustrate one constructional form in which Fig. 1 is an elevation of the combined race, reed and sley device and the shuttle drive.

Fig. 2 is a plan view of Figure 1, partly in section.

Fig. 3 is a vertical section on the line A—B of Figure 2.

Fig. 4 is an enlarged fragmentary elevation of the shuttle drive, partly in section.

Fig. 5 is a section along the line C—D of Figure 4.

Fig. 6 is a vertical section along the line E—F of Figure 5.

Figs. 7 to 9 illustrate another constructional form in which:

Fig. 7 is an axial longitudinal section through the notched bar channel.

Fig. 8 is a section on the line A—B of Fig. 7.

Fig. 9 is a section on the line C—D of Figure 8.

The shuttle 1 is guided for reciprocating movement in a notched bar tubular race 2. This notched bar tubular race is formed of individual plates between which the warp threads are adapted to extend. In the selected example, the shuttle and thus also the notched bar tubular race is of rectangular or square section; it is obvious, however, that both could be of a different shape to suit requirements. The weft thread, which is always to be deposited by the shuttle in the shed, issues from the notched bar tubular race through the slot 4, preferably by way of a tubular thread guide 4a.

The shuttle 1 is accurately guided in the notched bar tubular race. Advantageously guide rollers 5 are provided.

For the reciprocating movement of the shuttle, there is provided below the notched bar tubular race a slide 6, which can be moved backwards and forwards along a guideway 7. The reciprocating movement is effected in the constructional example by a wire cable 8, which is secured to a reciprocating piston 9. It is obviously possible to conceive of other driving means for the slide 6.

Provided on the slide 6 are two gear wheels 10 which are rotatable but are not driven, said gear wheels meshing with a larger gear wheel 11 which is rotatably mounted on the shuttle 1. This larger gear wheel 11, which is located on the inside of the lower threads of the shed, in addition to meshing with the two smaller gear wheels, is also in mesh externally of the lower threads of the shed with a rack 12 which extends transversely of the warp threads, also externally of the shed. The arrangement is such that the gear wheel 11 is wider, e. g., twice as wide as the gear wheels 10, to ensure the simultaneous engagement of the gear wheel 11 with the gear wheels 10 and the rack 12.

With the movement of the slide 6 transversely of the warp threads the gear wheels 10 endeavour to roll on the gear wheel 11. However, owing to their arrangement on both sides of the axis passing perpendicularly through the point of rotation of the wheel 11, the trailing wheel for the time being of the wheels 10 imparts a thrust on the gear wheel 11 and but for the presence of the rack 12 would cause wheel 11 to travel bodily without rotation along with the slide, but in the presence of the rack 12, the gear wheel 11 is caused to roll on the rack 12. Consequently, if the slide 6 is moved in one direction and then the other, the shuttle 1 is simultaneously moved backwards and forwards with the same speed in the notched bar channel or tubular race, the advancing movement being assured as aforesaid, and in addition the gear wheel is caused to mesh with the lower warp threads of the shed in rolling along the rack. The shuttle is thus moved positively in both directions throughout its travel through the shed.

As will be seen more particularly from Figure 4, the gear wheels 10 and 11 are so in mesh with one another that gaps remain between the tips of the teeth of one wheel and the tooth roots of the other gear wheel, it being possible for the warp threads 13 of the lower shed to lie in the

said gaps. It can also be seen from Figure 4 that the thread position is not disturbed by the provision of the rack. In order to prevent the threads from becoming damaged by the inter-engaging teeth, it is particularly advantageous to provide notched or saw-toothed guide strips 14 and 15 at both sides of the shuttle track and below the shuttle. The position of these guide strips is shown particularly clearly in Figure 2, while the shape and operation thereof will be appreciated from Figure 4. Two lower warp threads 13 of the shed are always located in each lower vortex point 16 of the saw-toothed guide strips. Each time upper warp threads 13' are lowered the inclined faces of the teeth of the strips 14 and 15 act as inclined planes to cause the said threads on reaching the end of their downward travel to group together in pairs at the bottom vortex points 16 of the teeth. The lower warp threads are thereby so bunched and collected in the vicinity of the space in which, on the one hand, the gear wheels 10 and 11 interengage and, on the other hand, the gear wheel 11 meshes with the rack 12, that the teeth can engage through the lower sheet of warp threads without obstruction. The strips 14 and 15 could of course be constructed so that the lower warp threads become bunched in groups of more than two threads.

From the foregoing description, it is seen that the shuttle can be positively moved backwards and forwards through the shed without the warp threads being damaged, the weft threads being placed in the open shed in the customary manner. As is also customary with other looms it is now necessary to effect the beating of the weft thread up to the "fell" or edge of the material. This purpose is served by the advancing edge 17 of the notched bar tubular race (see more especially Figure 3). Consequently, the notched bar tubular race is arranged to execute the known movement of the sley of a loom. For this purpose, the notched bar tubular race is mounted to slide freely on a guideway 19 preferably by using balls 18, although rollers could also be used instead of the balls. During the beating up of the weft thread in the shed, the notched bar tubular race is moved backwards and forwards on the guideway 19. The warp threads 13 and 13' are moved relatively in the spaces between the individual plates 3.

The driving slide 6 and its guide 7, and also the drive means 8, 9 appertaining thereto, must participate in each forward and backward movement. Accordingly, this part of the arrangement is suspended in a suitable manner on the notched bar channel and is also caused to participate in the movement.

In the constructional form according to Figs. 7 to 9 the shuttle 101 is also guided in the notched bar tubular race 102, which consists of the separate plates 103. The weft thread is led out of the notched bar channel at 104.

Rollers 105 can be provided for guiding the shuttle 101. Located below the notched bar race 102 and below the shuttle 101 are the saw-toothed guide strips 106 and 107 in which the lower threads 108 of the shed are laid for the purpose of bunching or grouping the same.

The drive of the shuttle 101 is effected by means of the gear wheel 109 which is mounted for free rotation on a reciprocating slide such as 6 of the first herein described construction. This gear wheel 109 engages in a rounded recess 110 of the shuttle 101 and forces the shuttle forwards or

backwards in the notched bar race, by the thrust exerted by the tips of the teeth in the direction of movement on the rounded recess 110.

As will be seen, the gear wheel 109 must rotate in order to be able to mesh with its teeth with the lower threads of the shed. There is provided for this purpose a stationary pinned rod 111 which is disposed below the notched bar channel and outside the shed. The pins of the pinned rod 111 compel the rotation of the wheel 109 and thus ensure the unimpeded movement of the shuttle while protecting the lower warp threads 108. In order to reduce the friction of the tips of the teeth on the rounded recess of the shuttle, they may be provided with rollers 112.

The position of the lower warp threads 108 and upper threads 108' of the shed with the shed open will be seen from Figure 9.

The individual parts of the arrangement according to the above described constructional forms of the invention are shown in a purely dia-grammatic manner, and it is consequently possible to modify the constructional forms of the individual parts without thereby departing from the scope of the invention.

What I claim is:

1. Shuttle driving mechanism for positively moving the shuttle of a loom through its shed, comprising in combination, a shuttle, guiding means therefor, a slide arranged externally of said shed, means for moving said slide transversely of the general direction of the warp threads, a rack parallel to the direction of and stationary with respect to the said movement of said slide, a gear wheel operatively related to said slide so as to be movable positively therewith and engaging said rack for rotation thereby during movement of said gear wheel with said slide, said gear wheel being in operative relation to said shuttle so that the said gear wheel and shuttle move together in passage of the shuttle through the shed and being adapted to mesh with the lower warp threads of the shed in rolling along said rack.

2. Shuttle driving mechanism according to claim 1, including means enabling the shuttle to be passed across the loom through the shed and then returned.

3. Shuttle driving mechanism according to claim 1, having said guiding means in the form of a reed-like notched bar passaged for the guidance of the shuttle, the edges of the notched bar directed towards the shed angle nearer the cloth serving as a beater stop for the weft threads.

4. Shuttle driving mechanism according to claim 1, having notched strips for the warp threads disposed at both sides of the shuttle path and below the shuttle, a plurality of warp threads being laid in the notches of said strips so that gaps are formed in the sheet of lower warp threads for the passage of the teeth of said gear wheel.

5. Shuttle driving mechanism according to claim 1, having the reed-serving elements of the notched bar so arranged in circular formation that they form an endless channel.

6. Shuttle driving mechanism for positively moving the shuttle of a flat loom through its shed, comprising in combination, a shuttle, guiding means therefor, a slide arranged externally of said shed, two non-meshing gear wheels mounted freely rotatable on said slide, means for moving said slide transversely of the general direction of the warp threads, a rack below the lower warp threads of said shed, paral-

7
lel to the direction of, and stationary with respect to the said movement of said slide, a larger gear wheel mounted on and freely rotatable with respect to said shuttle and engaging said two gear wheels on said slide so as to be moved positively by the slide in its lateral movement, the said larger wheel also engaging through the said lower warp threads with the said rack for rotation thereby during said movement of said larger gear wheel with said slide, whereby the lateral movement of the slide in moving the larger wheel, causes the passage of the shuttle through the shed during which movement the said larger wheel meshes with the lower warp threads of the shed in rolling along said rack.

8. Shuttle driving mechanism according to claim 6, including means enabling the shuttle to be passed across the loom through the shed and then returned.

9. Shuttle driving mechanism according to claim 1, having the gear wheel arranged externally of said shed and meshing with the warp threads by intrusion into a recess in the lower part of the shuttle, said recess being contoured

5 to correspond with the addendum circle of the gear wheel.

10. Shuttle driving mechanism according to claim 1, having a rack in the form of a stationary pinned rod.

WILLI KEIL.
